[57] CLAIM

The ornamental design for an artificial fingernail, as shown and described.

DESCRIPTION

FIG. 1 is a perspective view taken from the top back and right side of the artificial fingernail showing my new design; FIG. 2 is a left side view thereof; FIG. 3 is a top plan view thereof; FIG. 4 is a rear elevational view thereof; and, FIG. 5 is a bottom plan view thereof.

The broken lines showing the finger and front portions of the artificial fingernail are for illustrative purposes only and forms no part of the claimed design.
